CLAIM

The ornamental design for a shower and bath curtain, as shown and described.

DESCRIPTION

FIG. 1 is a front perspective view of a shower and bath
curtain, showing my new design;

FIG. 2 is a rear perspective view thereof;

FIG. 3 is a side elevational view thereof, the opposite side being symmetrical with the side shown;

FIG. 4 is a top plan view thereof; and,

FIG. 5 is a bottom plan view thereof.
